UNITED STATES PATENT OFFICE.

VICTOR ROYAL FRANCIS, OF DETROIT, MICHIGAN.

DESIGN FOR A WHEEL-CHOCK.

57,774.

Specification for Design.

Patented May 3, 1921.

Application filed April 5, 1920. Serial No. 371,494. Term of patent 7 years.

To all whom it may concern:

Be it known that I, VICTOR ROYAL FRANCIS, a citizen of the United States, residing at Detroit, county of Wayne, State of Michigan, have invented a new, original, and ornamental Design for a Wheel-Chock, of which the following is a specification, reference being had to the accompanying drawing, forming part thereof.

Figure 1 is a perspective of my new wheel chock.

Fig. 2 is a cross-section of the same.

I claim:

The design for a wheel chock as shown.

VICTOR ROYAL FRANCIS.
